COIL TESTING APPARATUS

Butler J. Haskins, Chicago, Ill., assignor to Joseph Weidenhoff, Inc., Chicago, Ill., a corporation of Illinois

Application December 9, 1933, Serial No. 701,648

6 Claims. (Cl. 175—183)

An object of this invention is to provide apparatus for testing spark coils and the like where it is desirable that not only will the time of flow of the charging current through the coil be simulated for various equivalent engine speeds, but that the difference in speed of opening the breaker points shall be varied in accordance with these same engine speeds in order that the conditions shall approximate very closely those of actual 10 operation of a distributor breaker on an automobile engine.

Another object is to provide means for compensating for differences in voltage of the battery on which the device is operated.

Another object is the simplification of coil testing apparatus.

These and other objects, as will hereinafter appear, are accomplished by this invention which is fully described in the following specification and shown in the accompanying drawing, in which—

Figure 1 is a schematic diagram of the apparatus showing parts of the motor and circuit breaker;

Fig. 2 is a greatly enlarged section through a part of the cam of the breaker device; and

Fig. 3 is a graph showing the action of this device for automatically correcting for battery voltage.

This is an improvement on the testing apparatus shown and described in my application Serial No. 664,466, filed April 5, 1933.

The embodiment illustrated comprises a direct current motor 10 which is shunt wound, as will later be described, so as to compensate for various operating voltages of a six volt storage battery 11 on which it is adapted to operate. The motor has a shaft 12 upon which is keyed a cam 13 which will later be described in detail as it contains the gist of the present invention.

A motor mechanism is associated with the cam 13 and has breaker points 14 carried by the breaker arm 15 which is hingedly mounted at 16 and carries a cam follower 17 which is constantly held against the face of the cam by means of a spring (not shown). A relatively stationary contact arm 18 is also hingedly mounted at 16 and carries a nut 19 in which is threaded a screw 20, the screw 50 carrying a pointer 21 operable over a dial 22 so as to indicate the position of the contact arm 18. The cam 13 is preferably cylindrical except for a low V-shaped notch 13^a which is formed therein, as shown in greatly enlarged detail in Fig. 2. The cam rotates in a clockwise direction and the cam follower, shown in dotted lines in Fig. 2, enters the notch at the right side to a depth permitted by the adjustment of the screw 20 at which the points 14 will be in contact. As 60 the cam continues to rotate the follower will

strike the left hand portion of the cam notch, thereby separating the breaker points.

It is desirable in making a test of a spark coil, such as will later be described, that the testing apparatus should be capable of adjustment so as to vary the simulated engine speed from a very high speed to a point approximately one-half that speed. To do this I arbitrarily take two points A, A' to represent the opening and closing 10 points, respectively, of the cam and separate these by an angle of 20° on the cam, these points corresponding to the opening and closing points of the cam for the highest equivalent engine speed desired.

The angle c may be taken as the lowest angle to be used on this cam and this angle may be calculated on the basis of a lift of .002" at the breaker points for each 1° of arc at the cam. If I take the follower as located half way between the breaker points and the fulcrum, the rise at 20 the follower, that is, on the cam, will be one-half that at the points, or .001" per 1° of arc of the cam. The average diameter of the cam at the points of opening may be taken as 3/4". By calculating the angle of the cam face at C, I find that the tangent of the angle c is approximately .001" divided by .0066", or .15. The angle c is accordingly about 8°, 30'. By doubling this angle for point A, the angle a is 17°, and by taking an average of these two angles for the point B, I obtain the angle b as 12°, 45'.

By properly choosing the points A, B and C and drawing tangents corresponding to these angles through them and connecting up these tangents to make a smooth curve, I have constructed the opening face of the cam. The angles on the cam face (Fig. 2) are exaggerated for the sake of greater clearness.

Knowing the cam angle of A to be 20°, that of B 30°, and that of C 40°, the corresponding points of closing A', B' and C' are found by plotting these angles along the concentric circles through the points A, B and C. A smooth curve A', B', C' is then drawn and is extended to the point D where it joins up with the extended end of the curve through A, B, C.

Thus it will be seen that by operating with the follower 17 on the radius through the points C, C', the breaker points will remain closed for 40° of cam arc corresponding to a slow engine speed, and the tangent of the angle c being small gives a relatively slow opening in the points also corresponding to a slow engine speed. If, however, the follower is readjusted so as to cause it to operate on the line through the points A, A', the cam angle through which the points will remain closed is reduced to 20°, corresponding to a speed double that when operating through the points C, C'. Likewise as the follower strikes the side of the groove at A, the follower is lifted 55 60

at a much more rapid rate owing to the fact that the tangent of the angle a is substantially double the tangent of the angle c . Thus as the angle of cam through which the points remain closed 5 is halved, that is cut from 40° to 20° , the rate of opening the breaker points is doubled. While the rotative speed of the cam remains constant this corresponds to the action which takes place in the usual distributor breaker when the speed 10 of the breaker cam is doubled. In that case, the time during which current flows through the primary of the coil under test is dependent on the speed of the distributor cam, and the speed with which the breaker points open is likewise 15 dependent on the speed of that cam. That is, in the usual distributor breaker as the cam speed is doubled the time during which current flows through the primary of the coil is reduced by half, and the speed of opening the circuit is 20 doubled. Both those conditions are now accurately simulated by this cam notch.

As a means for accurately and conveniently setting the breaker points for any predetermined cam angle as 20° , I have provided a collar 23 25 which may be adjustably secured on the outer end of the shaft 12 by means of a nut 24. The collar carries two markings at 0° and 20° on its outer face corresponding accurately to this angle on the collar. To adjust the breaker to these 30 markings the shaft 12 is turned until the points are just closing, which corresponds to the position A' of Fig. 2. The nut 24 is then loosened and the collar turned on the shaft until the 20° marking on the periphery of the collar lies in 35 front of a mark (not shown) on the end of the motor housing, or the like. The nut 24 is then tightened. The zero marking is then set to correspond to the position of opening of the breaker points. It may be necessary to adjust the screw 40 20 to make the points of opening coincide with the marking 0° and 20° on the collar.

During this time the pointer 21, if the screw 20 and parts associated therewith are properly 45 adjusted, will be likewise pointing at the 20° marking on the scale 22. The shaft 12 is then rotated until the 20° marking on the collar 23 comes into alignment with the marking on the motor housing. When this occurs the points 50 14 should just start to open. If not, the screw 20 will have to be readjusted so as to make the breaker points open and close in accordance with the marks 0° and 20° on the collar 23.

Having adjusted the parts so that the pointer 21 stands at 20° on the dial 22 when the breaker 55 points are closing and opening at 0° and 20° on the collar 23, the pitch of the screw 20 is such that the position of the pointer 21 will accurately indicate on the dial other settings of from 20° to 40° of the cam during which the breaker points 60 are closed.

In order to compensate for various voltages of the storage battery I use a motor 10 which is shunt wound and which preferably has in series therewith a resistor R whose resistance is about 65 twenty percent that of the resistance of the motor at normal operative speeds. This motor is so wound that with a battery voltage of 6 volts it has a speed of 1200 R. P. M. and at 7 volts a speed of 1450 R. P. M.

70 Thus the higher voltage gives a higher amperage through the primary winding of the spark coil which means a higher rate of energization of the coil. The higher voltage, however, means a higher speed for the shaft 12 and 75 cam 13, and hence a shorter time during which

the higher current flows through the spark coil. The two variables thus offset each other and substantially equal energizations of the coil are obtained with different battery voltages.

In order to test a spark coil E having the usual primary and secondary windings, the storage battery 11 is connected through leads 25, 26 with the primary winding of the spark coil, and thence back through leads 27, 28 to the breaker arm 15 where the circuit is grounded while the points 10 are in contact, and then back from the ground 29 through the lead 30 to the storage battery.

The secondary winding of the spark coil connects through a lead 32 with an electrode 33 of a spark gap 34, the opposite electrode 35 connecting through leads 36, 37 with the ground 29. The neon tube 38 is connected in parallel with the spark gap 34 so that as each spark jumps the gap, the neon tube becomes energized and a flash is produced therein. The spark gap and the 20 neon tube clearly indicate the degree of energization of the secondary and show the condition 15 of the spark coil.

With the motor in operation, the spark coil E is tested for various engine speeds corresponding to the cam angles 20° to 40° under conditions as hereinbefore pointed out which very closely simulate actual running conditions not only for the time of closing the spark breaker points, but also the faster opening thereof at higher engine 30 speeds.

The reason for changing the speed of opening the breaker points varies with engine speed is that at low speeds the points open slowly and an arc forming can follow the points. To overcome this a condenser is placed across the points. If the points open quickly enough, no arc can follow, and hence no condenser would be needed. In actual practice, however, this is not practicable, and a condenser is used to absorb the spark. 40 The present invention simulates these actual operating conditions which obtain in the distributor of an automobile wherein the higher the speed of the distributor shaft the faster the breaker points open. This is accomplished by 45 the V-shaped cam notch having an arcuate opening face, as previously described.

In Fig. 3 is illustrated diagrammatically the action of the motor in automatically correcting for battery voltage. Thus a storage battery having a potential of six volts will drive the motor at a speed of 1200 R. P. M. If now we assume the angle of contact of the cam 13 during which the breaker points are in contact is 40° , the actual time that they are in contact is about 55 .005 seconds. It is found that current from the storage battery at six volts flowing for .005 seconds will so energize a particular spark coil that discharge of the secondary will show a momentary current of two amperes, which gives very 60 satisfactory operation for this coil in an automobile ignition system.

I, therefore, plot the point F corresponding to .005 seconds in time and 2.0 amperes, and draw a horizontal line G through the point F. This line (shown dotted) is a line of desired saturation 65 for this spark coil. The line H, F represents roughly the saturation of the coil at different time intervals during which current flows under a potential of six volts from .000 seconds to .005 70 seconds of breaker point closure.

If now the battery potential is raised to seven volts and the time of closure of the breaker points remained the same, the saturation would increase so that the discharge of the coil would 75

show a momentary current of about 2.5 amperes. This is plotted at J on Fig. 3. The time, however, does not remain constant because at this increased voltage the motor 10 runs faster, so that its speed is now about 1450 R. P. M., and hence the time breaker points remain open is about .004 seconds. If now we draw a straight line between H and J we see that it crosses the ordinate .004 at the point K which is substantially on the horizontal line G of "desired saturation". Thus the energization of the coil remains nearly the same for different battery voltages within the normal operating range of six volts to seven volts. The above figures are for illustrative purposes only and are approximately correct for one type of spark coil. Tests of various spark coils show that the principle herein stated is substantially correct.

The combination of the shunt wound motor which compensates for battery voltage with the V-shaped cam notch of Fig. 2 provides a coil tester which is not only very efficient and accurate, but very simple and inexpensive to build and to operate. By this simple combination I am able to dispense with a battery voltmeter, a speed indicator for the motor, a motor speed regulator, and a compensator for adjusting the points of the spark gap to compensate for differences in battery voltages.

30 I claim:

1. In testing apparatus of the class described, a motor having a shaft, a make and break device having a cam on said shaft, said make and break device having points adapted to be connected in series circuit with a source of direct current and with the primary winding of a spark coil to be tested, a spark gap adapted to be connected in series circuit with the secondary winding of the spark coil, the cam having a low V-shaped notch in its face, a cam follower bearing on the face of the cam and operable to close and open the make and break device as it passes through said notch, and means for varying the depth to which said follower enters the notch to simulate various equivalent engine speeds for the breaker device, the opening side of the cam notch being arcuate to increase the rate of lift of the follower as the follower is lowered into the notch for the purpose specified.

50 2. In testing apparatus of the class described, a motor having a shaft, a make and break device having a cam on said shaft, said make and break device having points adapted to be connected in series circuit with the source of direct current and with the primary winding of a spark coil to be tested, a spark gap adapted to be connected in series circuit with the secondary winding of the spark coil, the cam having a low V-shaped notch in its face, a cam follower bearing on the face of the cam and operable to close and open the make and break device as it passes through said notch, and means for varying the depth to which said follower enters the notch to simulate various equivalent engine speeds for the breaker device, the opening side of the cam notch being arcuate to increase the rate of lift of the follower in substantially inverse ratio to the cam angle during which the breaker points are closed.

55 3. In testing apparatus of the class described, a shunt wound motor adapted to be driven by a storage battery, said motor having a shaft, a make and break device having a cam on said

shaft, said make and break device having breaker points adapted to be placed in series circuit with said storage battery and with the primary winding of a spark coil to be tested, a spark gap adapted to be connected in series circuit with the secondary winding of the spark coil, the cam having a low V-shaped notch in its face, a cam follower bearing on the face of the cam and operable to close and open the make and break device as it passes through said notch, the angle of the cam on the closing side being lower than the angle of the cam on the opening side so as to give a quick opening of the breaker points.

10 4. In testing apparatus of the class described, a shunt wound motor adapted to be driven by a storage battery, said motor having a shaft, a make and break device having a cam on said shaft, said make and break device having breaker points adapted to be placed in series circuit with said storage battery and with the primary winding of a spark coil to be tested, a spark gap adapted to be connected in series circuit with the secondary winding of the spark coil, the cam having a low V-shaped notch in its face, a cam follower bearing on the face of the cam and operable to close and open the make and break device as it passes through said notch, and means for varying the depth to which said follower enters the notch to simulate various equivalent engine speeds for the breaker device, the angle of the cam on the closing side being lower than the angle of the cam on the opening side so as to give a quick opening of the breaker points.

15 5. In testing apparatus of the class described, a shunt wound motor adapted to be driven by a storage battery, said motor having a shaft, a make and break device having a cam on said shaft, said make and break device having breaker points adapted to be placed in series circuit with said storage battery and with the primary winding of a spark coil to be tested, a spark gap adapted to be connected in series circuit with the secondary winding of the spark coil, the cam having a low V-shaped notch in its face, a cam follower bearing on the face of the cam and operable to close and open the make and break device as it passes through said notch, and means for varying the depth to which said follower enters the notch to simulate various equivalent engine speeds for the breaker device, the angle of the cam on the closing side being lower than the angle of the cam on the opening side so as to give a quick opening of the breaker points.

20 6. In testing apparatus of the class described, a shunt wound motor adapted to be driven by a storage battery, said motor having a shaft, a make and break device having a cam on said shaft, said make and break device having breaker points adapted to be placed in series circuit with said storage battery and with the primary winding of a spark coil to be tested, a spark gap adapted to be connected in series circuit with the secondary winding of the spark coil, the cam having a low V-shaped notch in its face, a cam follower bearing on the face of the cam and operable to close and open the make and break device as it passes through said notch, the opening side of the cam notch being arcuate to increase the rate of lift of the follower in substantially inverse ratio to the cam angle during which the breaker points are closed.

25 7. In testing apparatus of the class described, a shunt wound motor having a shaft, a make and break device having a cam on said shaft, said make and break device having points adapted to be connected in series circuit with a source of direct current and with the primary winding of a spark coil to be tested, a spark gap adapted to be connected in series circuit with the secondary winding of the spark coil, the cam having a low V-shaped notch in its face, a cam follower bearing on the face of the cam and operable to close and open the make and break device as it passes through said notch, and means for varying the depth to which said follower enters the notch to simulate various equivalent engine speeds for the breaker device, the angle of the cam on the closing side being lower than the angle of the cam on the opening side so as to give a quick opening of the breaker points.
